UNITED STATES PATENT OFFICE.

HENRY KALER, OF RANTOUL, ILLINOIS.

GRAIN DOOR.

Application filed January 12, 1924. Serial No. 685,860.

To all whom it may concern:

Be it known that I, HENRY KALER, a citizen of the United States, residing at Rantoul, in the county of Champaign and State of Illinois, have invented a new and useful Grain Door, of which the following is a specification.

The present invention relates to railway car constructions and more particularly 10 railway cars especially designed for transporting grain or the like.

The primary object of the invention is to provide means for automatically folding and supporting the upper sections of grain doors, when the doors have been moved to their open positions. 15

cent to the sides of the car doors, but centrally of the ceiling. Rods 12 connect the brackets and provide supports for the rollers 13 that lie in the paths of travel of the upper sections 9 of the doors, when the doors are moved to their open or inactive

Another important object of the invention is to provide a novel form of operating means which may be readily and easily operated from a point exteriorly of the car, the operating means being such as will hold the doors in various positions of adjustment.

20

Associated with each door is an operating means

doors are moved to their open or inactive positions, to the end that as the sections 9 engage the rollers, they will be folded towards the lower section 8 of the door, and supported adjacent to the ceiling of the car.

75

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

35 Referring to the drawings:

Figure 1 is a front elevational view disclosing a car door constructed in accordance with the present invention.

Figure 2 is a vertical sectional view 40 through the car and door openings.

Figure 3 is an elevational view of the cable operating mechanism.

Figure 4 is a front elevational view thereof.

45 Figure 5 is a sectional detail view disclosing the manner of securing the handle to the operating means.

Referring to the drawings in detail, the reference character 5 designates a car which is supplied with the usual openings. Tracks 6 are secured adjacent to the side edges of the door openings, and as shown, each of these tracks includes an upper horizontal section 7.

55 Each of the doors includes a lower section 8 and an upper hinged section 9, the lower

section being supplied with rollers 10 adjacent to its upper and lower edges, the rollers extending laterally from the door section to the position in the tracks so that the door will be held against lateral movement at all times. 60

The upper section 9 of each door, is relatively narrow and is held to its active position by the weight of the grain within the car. Brackets 11 are secured to the ceiling of the car and are arranged at points adjacent to the sides of the car doors, but centrally of the ceiling. Rods 12 connect the brackets and provide supports for the rollers 13 that lie in the paths of travel of the upper sections 9 of the doors, when the doors are moved to their open or inactive positions, to the end that as the sections 9 engage the rollers, they will be folded towards the lower section 8 of the door, and supported adjacent to the ceiling of the car.

Associated with each door is an operating mechanism which includes a cable 14 secured to the door at a point adjacent to the lower end of the door, from where the cable passes over the pulley 15 disposed adjacent to the upper end of the door, the cable passing over the pulley 16 arranged laterally of the door. The cable also passes over pulley 17 mounted in the support 18 secured to the outer surface of the car, from where the pulley passes onto the drum 19 mounted within the housing 20.

Supported on one end of the shaft that supports the drum 19 is a gear 21 that operates in the casing 21' that may be partially filled with grease to lubricate the gearing.

The gear is operated by the worm 22 carried by the shaft 23, which shaft is supplied with an operating handle 24 that has a squared extremity 25 to be positioned in the squared opening of the member 26 forming a part of the handle. 100

In order that the member 26 may be normally held to the handle 24, a coiled spring 27 is provided, which spring has connection with the handle 24 at 28, the lower end of the coiled spring being connected to the member 26 so that the contractile force of the spring will tend to prevent displacement of the member 26. From the foregoing it will be obvious that if it is desired to move the member 26 to its inactive position, the member 26 may by forcing the same downwardly, be disconnected from the member

24 and slightly turned to a position to bring the member 20 to a point under the car proper and out of the way of persons walking near the car.

5 In operation, when the handle is operated, the cable will be wound on the drum 19 and the door associated therewith, moved upwardly, the upper section of the door engaging the roller 12 associated therewith to the 10 end that the upper section is folded rearwardly and the lowermost section moved to overlie the upper section.

I claim:—

1. In a car door construction, a trackway 15 disposed adjacent to the door, a door having rollers movable within the trackway, said door including an upper hinged section, a supporting member including rollers, mounted within the car adjacent to the ceiling there- 20 of, and the upper hinged section of the door adapted to engage one of the rollers to cause

the upper section to swing rearwardly, and means for moving the door to its active and inactive positions.

2. In a car door construction, a trackway 25 positioned adjacent to the door opening, a door movable in the trackway, said door including an upper hinged section, bracket members within the car and arranged adjacent to the upper ends of the trackway, 30 rollers supported by the bracket, said rollers lying in the path of travel of the door to its open position, said rollers adapted to support the upper hinged section in its open position, and means for operating the door. 35

In testimony that I claim the foregoing as my own, I have hereto affixed my signature in the presence of two witnesses,

HENRY KALER,

Witnesses:

CHARLEY McALLISTER,
JAMES GRADY.
